CLAIM

The ornamental design for a coin depositing and dispensing apparatus, as shown and described.

DESCRIPTION

FIG. 1 is a perspective view 1 of a coin depositing and dispensing apparatus showing my new design;

FIG. 2 is a perspective view 2 thereof;

FIG. 3 is a perspective view 3 thereof;

FIG. 4 is a perspective view 4 thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom view thereof.

The broken lines depict portions of the coin depositing and dispensing apparatus that form no part of the claimed design.
